UNITED STATES PATENT OFFICE.

SARAH ANN MILLER, OF NEW YORK, N. Y.

ALCOHOL OR POWDER APPLIANCE.

1,073,155.

Specification of Letters Patent. Patented Sept. 16, 1913.

Application filed January 23, 1913. Serial No. 743,710.

To all whom it may concern:

Be it known that I, SARAH A. MILLER, a citizen of the United States, residing at 173 West Eighty-first street, New York, county of New York, and State of New York, have invented certain new and useful Improvements in Alcohol or Powder Appliances, fully described and represented in the following specification and the accompanying drawings, forming a part of the same.

The present invention relates to a means by which a single receptacle or box having a suitable handle may be provided with a detachable soft fabric covering and adapted to furnish such covering with a supply of dry powder or of alcohol or other bathing fluid to moisten the same, the handle being preferably constructed to apply the box with ease to any part of the body.

The invention embraces a box having a detachable cover which permits its being filled with powder or alcohol, such cover being perforated with suitable holes to discharge the powder or alcohol. A soft porous fabric is secured detachably over the perforations and is itself unperforated if designed to be used with the alcohol, as it absorbs the alcohol freely and furnishes a moist rubber. If designed to be used with the powder, it is preferably perforated with holes corresponding to those in the box so that the powder may be shaken out through the two sets of perforations, and the soft fabric covering utilized to spread and rub the powder upon the body.

As a larger number of holes is required for discharging powder than for discharging a liquid like alcohol, the box is provided with two interchangeable caps secured removably thereon by a screw-thread or a bayonet-lock, one cap having but few perforations to use with alcohol, and an unperforated fabric covering, and the other cap having more perforations adapted to use with a correspondingly perforated fabric covering for applying powder.

The invention will be understood by reference to the annexed drawing, in which—

Figure 1 is a plan of the device fitted up for the application of powder; Fig. 2 is an edge view of the same; Fig. 2^a is an edge view of the box with a cap screwed thereon; and Fig. 2^b is an edge view of the box with a cap secured thereon by a bayonet-lock; Fig. 3 is a perspective view of a detachable cap perforated for use with pow-

der; Fig. 4 is a similar view of the cap perforated with two holes for use with alcohol; Fig. 5 is a section of a cap with an unperforated covering secured thereon for use with alcohol; and Fig. 6 is a section of a cap perforated for use with powder and having a perforated covering secured thereon.

The box *a* has a handle *b* projected from one edge near the bottom, a wire handle being shown extended to sufficient length for applying the box to the back or other parts of the body.

In Fig. 2^a, the edges of the box and cap are shown formed with a screw-thread engagement, to make the cap detachable.

Fig. 2^b shows a box with radial pin *d* thereon and right-angle notch *d'* in the cap to fit the same, as is common with a bayonet-lock.

The caps in Figs. 3 and 4 are shown with similar screw-threads so as to be interchangeably secured upon the box, the one in Fig. 3 having twelve holes *e* for discharging powder freely; while that in Fig. 4 has only two holes *e'* for discharging alcohol.

The fabric-covering for the cap, as shown in Fig. 7, is a square section of felt or porous cloth *f* which is secured detachably upon the cap by stretching its edges over the edge of the cap and securing them removably thereto by a cord or elastic band *g*. Such construction enables the renewal of the fabric-covering when it is soiled or worn, as it is particularly liable to be when used for giving an alcohol rub. Such detachability and renewability is one of the chief advantages of my construction.

The porous fabric is shown in Figs. 1 and 6 provided with perforations *e²* in correspondence with the holes *e* in the cap, and the fabric is shown adjusted so that the holes in the fabric and the cap coincide and the powder may be shaken out through the same.

The fabric covering is shown in Fig. 5 unperforated and stretched over the two holes *e'* in the cap, which is thus adapted to furnish a supply of fluid to the fabric covering through which it filters, keeping the same moist while in use.

It is obvious that the fluid can only be applied to the surface of the body by rubbing the fabric-covering upon the skin, which in time soils and fouls the covering, so as to need renewal or cleansing. By holding the fabric detachably upon the cap by means of

a cord or elastic, it is readily renewed, and the device thus kept in a sanitary condition.

The caps being interchangeable, it is obvious that the box may be supplied with 5 either powder or bathing fluid, and a suitable cap and covering secured thereon for using the powder or fluid in the desired manner.

The form of handle attached to the box 10 is immaterial, and either a long or short handle may be provided; but a long flexible handle such as is shown in the drawing is most convenient for applying the device to the back and many other parts of the body.

15 Having thus set forth the nature of the invention, what is claimed herein is:

In a device for applying powder or alcohol, the combination, with a box having a handle projected from one side, of interchangeable perforated caps with means for 20 locking them removably upon the box, and a porous fabric secured upon each of the said caps, one of such fabrics having holes to coincide with the holes in its cap.

In testimony whereof I have hereunto set 25 my hand in the presence of two subscribing witnesses.

SARAH ANN MILLER.
